DES. 1990

Samuel Trischet of New York, NY

Letters Patent No. 1990 Dated Sept. 20th 1866.

Design for a Ruffle

The schedule referred to in these Letters Patent and making part of the same.

Specification of a design for a Ruffle invented by Samuel Trischet,
of the City, County and State of New York.

Nature of the Invention.

My invention consists in striking up the central part of the ruffle, so as to form a more elegant and beautiful article than has heretofore been made, as hereinafter more fully described.

Description of the Drawings.

Figure 1 is a side view of the ruffle, showing the configuration of the struck up central part.

Figure 2 is a longitudinal section of the same through the line 4-4 showing the central part struck up above the level of the fluted sides.

Figure 3 is a transverse section of the same, more clearly showing the central part struck up above the level of the fluting.

General Description.

1, are the sides of the ruffle, fluted in the ordinary manner. 2 is the central part of the ruffle, which instead of being plain as in the ordinary ruffle, is struck up into the form of angular pyramids with the narrower or end faces depressed; the depressions between the pyramids of said central part, when viewed vertically, having a lozenge shaped appearance, and the depressions in

2

DES. 1990

The narrower or end faces of the pyramids having the appearance of being the corners or ends of another set or row of lozenge shaped depressions alternating with the first or described set or row, thus giving to the central part of said ruffle the appearance of being a segment of checkered work composed of rows of raised or struck up pyramids separated by alternate rows of lozenge shaped depressions.

Claim

I claim the design for a ruffle as shown and described.
